(57) **CLAIM**

The ornamental design for a display screen, or portion thereof, having a graphical user interface with an options trading visual aid, as shown and described.

DESCRIPTION

This application is related to U.S. Design patent application Ser. No. 29/636,113, entitled "Display Screen, or Portion Thereof, Having a Graphical User Interface With an Options Trading Visual Aid," the contents of which are incorporated by reference in their entirety herein.

FIG. 1 is a first image in a sequence for a display screen, or portion thereof, having a graphical user interface with an options trading visual aid showing the new design;

FIG. 2 is a second image thereof;

FIG. 3 is a third image thereof;

FIG. 4 is a fourth image thereof;

FIG. 5 is an enlarged view of callout region 5 of FIG. 1;

FIG. 6 is an enlarged view of callout region 6 of FIG. 2;

FIG. 7 is an enlarged view of callout region 7 of FIG. 3; and,

FIG. 8 is an enlarged view of callout region 8 of FIG. 4.

The appearance of the transitional graphical user interface sequentially transitions between the images shown in FIGS. 1-4.

The process or period in which one image transitions to another forms no part of the claimed design.

The equally-spaced broken lines are for the purpose of illustrating environment only and form no part of the claimed design.

The dot-dashed broken lines are for the purpose of illustrating magnified portions of the display screen, or portion thereof, having a graphical user interface with an options trading visual aid.

The outer edge of the portion of the display screen is understood to be congruent with the outer edge of the graphical user interface.
